UNITED STATES PATENT OFFICE.

WILLIAM S. LINCOLN AND JAMES F. WHITT, OF NICKERSON, KANSAS.

FURNACE.

1,129,995.

Specification of Letters Patent. Patented Mar. 2, 1915.

Application filed February 24, 1914. Serial No. 820,627.

To all whom it may concern:

Be it known that we, WILLIAM S. LINCOLN and JAMES F. WHITT, citizens of the United States of America, residing at Nickerson, in the county of Reno and State of Kansas, have invented certain new and useful Improvements in Furnaces, of which the following is a specification, reference being had therein to the accompanying drawing.

10 This invention relates to furnaces especially adapted for the heating of bands or tires for wheels, and has for its object the production of a portable furnace in which the tires or bands may be thoroughly and uniformly heated while carried within the furnace.

Another object of this invention is the production of a simple and efficient furnace which may be made easily portable or stationary to accomplish the desired results, and which consists of a minimum number of parts.

With these and other objects in view this invention consists of certain novel combinations, constructions, and arrangements of parts as will be hereinafter fully described and claimed.

In the accompanying drawing: Figure 1 is a detail perspective of the furnace. Fig. 2 is a central vertical section therethrough. Fig. 3 is a transverse section taken on line 3—3, of Fig. 2. Fig. 4 is a vertical section taken on line 4—4, of Fig. 2. Fig. 5 is a transverse section taken through the rear supporting brace which carries the band or tire supporting brackets. Fig. 6 is a detail perspective of one of the tire supporting brackets. Fig. 7 is a detail perspective of the door used in connection with the present invention. Fig. 8 is an end view of the furnace showing the latch mechanism which is adapted to hold the door in a closed position.

Referring to the drawings it will be seen that 1 designates the body of the furnace which comprises a substantially rectangular frame, and this frame tapers toward its upper end to constitute a reduced tapered neck 2 terminating in a discharge funnel 3, which funnel is mounted upon the reduced end 2 of the body 1 as is illustrated in Figs. 1 and 2. The body 1 comprises a plurality of angle iron corner pieces 4 over which corner pieces are placed the sheet metal plates 5 going to make up the outer casing or shell of the furnace.

A plurality of angle irons 6 are carried by the front and rear walls of the outer shell and these angle irons 6 constitute supporting bars or ribs for supporting the grate 60 bars 7, which grate bars extend transversely of the furnace as is clearly illustrated in Figs. 2, 3 and 4.

An inner wall 8 is spaced from the rear wall of the body 1 as is illustrated in Fig. 65 3, and has its side edges engaging the rear angle irons 4 going to make up the frame of the furnace. A central vertically extending channel iron 9 is carried by the body 1 and extends vertically therein, and 70 is spaced between the inner wall 8 and the rear plate of the body 1 of the furnace. Studs 10 pass through the wall 8 and through the rear wall of the body 1 and constitute efficient means for holding the 75 inner plate 8 in firm engagement with the body of the furnace. The rear wall 8 extends approximately one-half the height of the body 1, as is illustrated in Fig. 2 to constitute a protector against the fire adapted 80 to be mounted upon the transversely extending grate bars 7 of the furnace 1. Inner walls 11 are carried by the ends of the body and are spaced therefrom by means of the corner angle irons 4 and the projecting flanges 12 formed upon the rear plate 8. Transversely extending studs 13 pass through the walls 11 and body 1 for firmly holding the walls 11 in engagement with the body 1.

A door 14 is hingedly secured to the body 1 by means of hinges 15, and a latch bar 16 is fixedly secured to the outer face of the door, which latch bar 16 is adapted to fit in the keeper 17 for holding the door 14 in a 95 closed position. The door 14 comprises an outer plate 18, which plate is provided with a substantially inverted V-shaped frame 19 extending along the upper edge thereof, and this flange 19 is preferably formed of angle iron as is illustrated in Fig. 7. An inner plate or wall 20 is carried near the lower end of the door 14 and is firmly held in engagement with the door by means of the transversely extending rivets 21 as is illustrated in Figs. 3 and 7.

By carefully considering Fig. 3 it will be seen that the furnace comprises an inner casing constituted by means of the walls 8, 11 and 20 and outer shell comprising the 110 body 1. In view of the fact that the walls 8, 11 and 20 are spaced from the body 1 and

the outer plate 18 of the door 14 it will be seen that a draft can easily pass up between the inner casing and the outer wall or casing for assisting in burning the material placed upon the grate bars 7. The lower portion of the frame 1 is opened as indicated at 22 to allow the entrance of air under the furnace. Reinforcing angle irons 23 extend transversely of the upper end of the casing 1 for constituting a brace therefor, and the upper end of the vertically extending centrally located brace 9 abuts against the lower end of this angle iron 23.

A plurality of substantially V-shaped hook or band supporting brackets 24 are mounted upon the centrally located channel iron 9, and these brackets are provided with the laterally extending substantially U-shaped feet 25, which fit over the flange portion 26 of the channel iron 9. Rivets 27 pass through the feet 25 of the brackets 24 for firmly holding the same in engagement with the channel iron 9. These channel irons 9 are riveted or otherwise securely fastened to the body 1 of the furnace. It should be understood that by means of the substantially U-shaped feet of the brackets that the same will be greater reinforced and relieve considerable of the lateral strain of the brackets when placing the hooks or bands 28 upon the brackets 24 as illustrated clearly in Figs. 2 and 4.

It should be understood that by means of the present furnace, tires or bands may be very quickly heated, and at the same time very evenly heated for the purpose of obtaining the fullest expansion possible without burning the wheel or other object upon which the band or wheel or tire is adapted to be placed. It should be further understood that owing to the peculiar shape of the furnace, considerable fuel will be saved in view of the fact that the heated gases will be forced upwardly and will be forced 45 to rise closely to the pieces or hooks to be heated. It should be further understood

that owing to the fact that the furnace is provided with the inner shell spaced from the outer casing, the air which is admitted under the furnace will be forced upwardly 50 between the inner and outer casings, and thereby cause an efficient upward draft and cause the burnt gases to be directed upwardly and in this manner more efficiently heat the articles placed within the furnace. 55 It should be understood that the sloping or inclined sides will constitute a deflector for the flames against the upper part of the tire or band, thereby allowing the band to be efficiently heated. 60

By means of the present construction it will be seen that the furnace by being open at the bottom and top will insure a free circulation of cool air through the channel between the inner and outer casings, thereby keeping the outer shell or casing cooler than is possible in a closed air space. It should be further understood that owing to this particular construction the device may be very easily repaired, and it should be further 70 understood that any form of material, as above stated, may be used for heating the furnace.

Having thus described the invention what is claimed, as new, is:—

In a device of the class described, a body portion, inner and outer casings, a central vertically extending channel iron, a plurality of substantially V shaped supporting brackets mounted upon said channel iron, 80 said supporting brackets provided with laterally extending substantially U shaped feet and constituting support for bands adapted to be placed thereon.

In testimony whereof we hereunto affix 85 our signatures in presence of two witnesses.

WILLIAM S. LINCOLN.
JAMES F. WHITT.
